UNITED STATES PATENT OFFICE.

LINDALE E. THOMAS, OF KERMIT, WEST VIRGINIA.

SWITCH.

1,060,796.

Specification of Letters Patent.

Patented May 6, 1913.

Application filed November 29, 1912. Serial No. 734,042.

To all whom it may concern:

Be it known that I, LINDALE E. THOMAS, a citizen of the United States, residing at Kermit, in the county of Mingo and State 5 of West Virginia, have invented certain new and useful Improvements in Switches, of which the following is a specification.

My invention relates to certain new and useful improvements in switches particularly adapted for tram lines, street car lines and the like, and is so constructed that the car may trail through the switch and throw the same, and also that the switch may be operated, with the car going in the reverse 15 direction, by the driver or motorman, without leaving his seat.

The object of my invention is to produce a switch of this character which is simple and inexpensive in construction, and one 20 which may be operated easily and with certainty.

With the foregoing and other objects in view my invention consists in certain constructions, combinations and arrangements 25 of parts, the preferred form of which will be first described in connection with the accompanying drawings, and then the invention particularly pointed out in the appended claims.

30 Referring to the drawings wherein the same part is designated by the same reference numeral wherever it occurs, Figure 1 is a plan view of the preferred embodiment of my invention and Fig. 2 is a detail, perspective view of the parts separated to more clearly show the construction.

5, 5 designate the main line rails, and 6, 6, the rails of the switch or siding. Pivoted to the inside rail 5 of the main line is a 40 switch point 7, and pivoted to the inside rail 6 of the switch is a switch point 8, these points being shown as pivoted to their rails at 9.

10 designates a bar extending beneath the 45 rails, which is connected to the switch points 7 and 8 by means of lugs 11, provided with upturned portions 12, adapted to be secured to the sides of the switch points 7 and 8, and also to be secured to the bar 10, as shown in 50 Fig. 1, whereby a reciprocation of the bar will move the switch points.

18 designates a link pivoted at one end to the bar 10, and pivoted at its other end to one end of a bell crank lever 14 pivoted in a 55 lug 15 secured to a tie. Pivoted to the opposite end of the bell crank 14 is a link 16

and connected to the pivot 17, between the link 16 and the bell crank 14, is a rod 18 connected to the switch operating lever 19 provided with a handle 20 and pivoted upon a switch stand 21 by means of the pivot 22. The switch stand is preferably provided with a guiding sector 23, carrying a guiding bar 24 in which the lever 19 moves. The opposite end of the link from that which is 60 connected to the pivot 17 is pivoted to one end of a rail 25 which is laid beside the main line, and at its opposite end from that to which the link 16 is secured is spiked to the ties, as indicated at 26, whereby the rail will 65 act as a spring, and will operate to complete the throw of the switch after the same has been started in either direction.

From the construction just described it will be seen that with the parts in the position shown in Fig. 1, in which the siding is open, the wheels of the car trailing through the switch on the main line will force the switch points over until the toggle has been straightened, thus placing the spring rail 25 80 under tension, and then to a short distance beyond. The spring in the rail 25 will now operate to complete the throw of the switch. When the switch is operated through the lever 19 it is only necessary to move the 85 same until the toggle shall have passed its dead center, which again puts the rail 25 under tension, when the spring in the rail will complete the throw of the switch. It will thus be seen that the rail 25 operates 90 through the toggle formed by the link 16 and the bell crank lever 14, to complete the throw of the switch in either direction after the same has been partly thrown either by the flanges of the wheel trailing through the 95 switch or by the lever 19.

I realize that considerable variation is possible in the details of construction and arrangement of parts without departing from the spirit of my invention, and I therefore do not intend to limit myself to the specific form shown and described.

Having thus described my invention what I claim as new and desire to secure by Letters Patent is:

1. In a switch the combination with a pair of main line rails, a pair of siding rails, and a pair of switch points pivoted to one of the main line rails and one of the siding rails, of a bar connecting said switch points 110 together, a toggle connected to one end of the bar, a spring rail extending alongside

of the main line rails, said toggle being also connected to said spring rail, and a switch operating lever connected to the pivot of said toggle.

- 5 2. In a switch the combination with a pair of main line rails, a pair of siding rails, and a pair of switch points pivoted to one of the main line rails and to one of the siding rails, of a bar extending beneath the 10 switch points and connected thereto, a bell crank lever, a link connecting one end of the bar to one arm of the bell crank lever, a spring rail secured alongside the main line

rails, a link connecting the free end of the spring rail to the other arm of the bell crank lever, whereby said link and the arm of said bell crank form a toggle, and a switch operating lever connected to the pivot of said toggle.

In testimony whereof I affix my signature 20 in presence of two witnesses.

LINDALE E. THOMAS.
